UNITED STATES PATENT OFFICE.

FRELING C. FOSTER, OF CHICAGO, ILLINOIS.

SAFETY APPLIANCE FOR BOATS.

1,133,629.

Specification of Letters Patent. Patented Mar. 30, 1915.

Application filed August 6, 1914. Serial No. 855,384.

To all whom it may concern:

Be it known that I, FRELING C. FOSTER, a citizen of the United States, residing at Chicago, in the county of Cook and State of Illinois, have invented a certain new and useful Improvement in Safety Appliances for Boats, of which the following is a specification.

My invention relates to improved types of safety appliances for boats, ships and the like and has for one object to provide means which may always be present and always available for preventing the sinking of a sea going vessel independent of the condition of the shell thereof.

It is illustrated more or less diagrammatically in the accompanying drawings, wherein—

Figure 1 is a perspective of a ship with my invention attached; Fig. 2 is a cross section through the ship; Fig. 3 is a plan view of the ship with my device attached arranged as shown in Figs. 1 and 2 with parts omitted to show my device; Fig. 4 is a detail section on an enlarged scale of the safety device shown in Fig. 2; Fig. 5 is a detailed section through a ship with a modified form of my device applied; Fig. 6 is a detailed section of one of the check valves; and Fig. 7 is a detailed section of one of the auxiliary bag filling valves.

Like parts are indicated by like letters throughout the several figures.

A is a ship having a continuous shell A¹. Located in this shell above the water line is a series of substantially hemi-spherical pockets A² which project back into the ship but separated from the interior by the continuous wall A³ which is a continuation of the wall A¹. Each of these pockets contains a collapsible bag A⁴ and is closed by a movable cover A⁵. Each bag is anchored at the bottom of the pocket at one point by a plate B through which passes the filling tube B¹ and which is bolted through the bag as indicated at B² to the wall A².

B³ is a relief pet-cock opening out from the pipe B¹ and B⁴ is a check valve communicating with the pipe B¹.

50 B⁵ is a supply conduit leading to the check valve B⁴ from the supply main B⁶.

B⁷, B⁸ are air pressure storage tanks at the bottom of the ship and communicating with the main B⁶.

55 B⁸, B⁹ are valves controlling the communication between the main B⁶ and the pipe B⁵.

B⁹ are compressors discharging into the main B⁶ to the tank B⁷ to fill them with air under pressure.

In the modified form shown in Fig. 5 the hull of the ship is not indented but contains inside compartments having a hinged lid C¹ which incloses the pocket C² anchored to the compartment at C³ and adapted to be inflated as the pockets previously described.

D, D are valve chambers arranged at suitable intervals above and in communication with the main B⁶. These valve chambers have at their upper end a valve sleeve D¹ in which is a slidably mounted hollow valve tube D² with a conduit D³ terminating at the bottom in an elbow D⁴. This tube is provided with a collar D⁵ and surrounded by a spring D⁶ which tends always to hold the tube in the upper position and hold the valve head D⁷ against the seat D⁸ and retain the elbow D⁴ within the sleeve D¹ thus closing this valve. When the stem, however, is depressed against the spring the head will leave the seat and the elbow will be open and air can pass out.

D⁹, D¹⁰ are bags kept in the hull of the ship in a collapsed form adapted to be placed over the end of the valve stem to be inflated when the valve stem is pushed down. These bags are provided with a form of check valve to prevent egress of air.

F is a latch pivoted on the door A⁵ engaging a notch F¹ in the wall A³ and provided with an arm F² resting against the chamber or bag A⁴ in such way that the preliminary inflation and expansion of this chamber will force the arm outwardly releasing the latch to permit the door to open.

F³ is a pin fixed in the wall A³ and slidably engaged by the groove F⁴ in the flange F⁵ which projects inwardly from the door A⁵.

F⁶ is a shoulder about the pocket A² engaged by and furnishing a seat for the door.

I claim:

1. A safety appliance for boats comprising a series of pockets along the side thereof with a series of collapsible bags one in each pocket and movable closures one for each pocket hinged and provided with a latch, said latch adapted to be sprung by the bag as it is expanded and means for inflating the bag.

2. A safety appliance for boats comprising a series of pockets along the side thereof with a series of collapsible bags one in

- each pocket, a closure for each pocket hinged and provided with a latch, said latch adapted to be sprung by the bag as it expands and means for inflating the bag.
5. 3. A safety appliance for boats comprising a series of pockets along the side thereof with a series of collapsible bags one in each pocket and movable closures one for each pocket flush with the side of the boat hinged and provided with a latch, said latch adapted to be sprung by the bag as it is expanded and means for inflating the bag.
4. A safety appliance for boats comprising a series of pockets along the side thereof with a series of collapsible bags one in each pocket, a closure for each pocket flush with the side of the boat hinged and provided with a latch, said latch adapted to

be sprung by the bag as it expands and means for inflating the bag.

20

5. A safety appliance for boats comprising a series of pockets along the side thereof, a series of collapsible bags one in each pocket, means for introducing gas into the bag at the base where the air is introduced 25 and a closure for each pocket flush with the side of the boat hinged and provided with a latch, said latch adapted to be sprung by the expansion of the bag.

In testimony whereof I affix my signature in the presence of two witnesses this 29th day of July, 1914.

FRELING C. FOSTER.
